UNITED STATES PATENT OFFICE.

JOHANN STANZIG AND RUDOLF KÖNIG, OF VIENNA, AUSTRIA, ASSIGNEES OF ONE-THIRD TO JOSEF ROSENTHAL, OF VIENNA, AUSTRIA.

FIRE-EXTINGUISHER.

1,235,505.

Specification of Letters Patent. Patented July 31, 1917.

Application filed August 13, 1914. Serial No. 856,512.

To all whom it may concern:

Be it known that JOHANN STANZIG and RUDOLF KÖNIG, subjects of the Emperor of Austria, residing at Vienna, VI, in the Empire of Austria, have invented certain new and useful Improvements in Fire-Extinguishers, of which the following is a specification, reference being had therein to the accompanying drawing.

10 It has been previously known to extinguish burning liquids, such as benzin and the like by means of two fluids kept apart from each other ready for use and when mixed evolving gas and foam, the gas being 5 mechanically bound in the foam and the latter thereby rendered more fire resisting. The action of the foam is to cover the burning objects and stifle the flames.

In the known devices the fluids always 20 kept ready for use however take up too much room and are also liable to freeze. To remedy this defect it has hitherto been proposed to employ reagents in solid form and not dissolve same until required. Hence in 25 this known method, the water dissolves all the reagents simultaneously and the same form one mixture in which the whole of one reagent acts simultaneously upon the whole of the second reagent which, as practice has 30 proved, results in an incomplete utilization of the reagents.

In view of this fact fire extinguishing devices have been constructed in which the solution has been produced by passing water 35 under pressure through the reagents kept in solid form.

In these appliances the water under pressure is however so conducted, that it passes 40 through the separated reagents in two streams and that the reaction forming the foam, will not take place until the two streams meet.

To fully utilize the reagents this arrangement however makes it necessary that the 45 reagents contained in the two solutions meeting, correspond exactly with the combining proportions and as this condition is practically not fulfillable, these apparatus do by a long way also not give the maximum effect.

50 To obtain the described result in a reliable manner, according to our invention, the chambers containing the reagents are inserted in the stream of water under pressure one behind the other, so that the stream of water 55 carrying one of the reagents in solution,

after passing through the first chamber will enter the second chamber and act therein upon the second reagent in quantity corresponding exactly with the combining proportions. The commencement of the reaction 60 and the formation of foam is substantially assisted by so choosing the relative position of the place where the water stream carrying the first reagent enters the second chamber to that of the exit, that the stream 65 of water can only leave the second chamber after reversing its direction of flow.

The annexed drawing shows in section one embodiment of the device constructed in accordance with our invention for carrying 70 out our said method.

The said device consists of a vessel *v*, preferably made of metal and tubular, closed at both ends and by a partition divided into a small chamber *m* and a large chamber *n*. 75 The chamber *m* is furnished with a closable inlet *f* and a pipe connection *d* while the chamber *n* has a closable inlet *a* and an outlet *h* preferably coaxial with the vessel *v*, and communicating with the first chamber 80 *m* by means of a pipe *o* which extends along the wall of the vessel to the end of the chamber *n* and is bent at its end to an angle of 180 degrees, so that the stream of water issuing at the pipe orifice is directed against 85 the interior of the chamber *n* and must pass through the latter in two directions to reach the outlet pipe connection *h*.

The chamber *m* for instance, is charged 90 with oxalic acid, tartaric acid or the like in powder form, the chamber *n* with a mixture of pulverized bicarbonate of soda, quillai bark and a saponaceous or another substance forming foam, in some cases charged with ammonia or alum.

The device in this condition ready for 95 use, can be kept any desired length of time and in any desired place, in any temperature and in any position, without detriment to its effectiveness.

Owing to the small weight and size of the device, when required it can be readily brought to and connected with the outlet of a water conduit intended therefor. In a permanent installation such connection is 105 made when putting up the installation, so that a tap only has to be opened to set the same in operation. The water then flows through the chamber *m* gradually dissolves the acid therein, enters through the pipe *o* 110

the chamber *n* and to run off at the edges of the disk *t*, must then pass through the chamber *n* in two opposite directions, as indicated by the arrows, causing it to flow 5 against the mixture of reagents therein and dissolving the same. The acid in the water then reacts on the dissolving salts and at the same time extracts the quillai bark, so that the gases formed by the action of the acid 10 will form with the slimy fluid a thick foam which is conducted by the pipe connection *h* to the place of fire with or without pressure either direct or by means of a hose. The disk *t* in the chamber *n* serves as deflecting 15 surfaces and assists the formation of a uniformly thick foam.

Having now particularly described and ascertained the nature of our said invention and in what manner the same is to be performed, we declare that what we claim is:

1. A device for the production of foam comprising a vessel, a transverse partition having an opening and dividing said vessel into chambers of unequal size, an inlet into 25 the smaller of said chambers, an outlet at the opposite end of the vessel, a pipe having one end engaged in the opening in said partition and extending toward the outlet of said vessel, and a transverse baffle in said 30 vessel, said pipe extending beyond said

baffle and curved to open into the larger of said two chambers, through said baffle.

2. A device of the character described, comprising a containing vessel, an outlet and an inlet port in said vessel, a partition 35 dividing said vessel into chambers of unequal size, a pipe connecting said chambers, and a baffle near the outlet end of said vessel, said pipe having a backward curve of 180° near its outlet end and extending 40 through said baffle, said outlet port being at the end of said vessel opposite to its inlet end.

3. A device of the character described, comprising a vessel having an inlet and an 45 outlet opposite the inlet, a partition disposed transversely of said vessel and dividing the same into chambers of unequal size, a baffle disposed concentrically within the vessel adjacent the outlet end thereof, and a 50 pipe connecting said chambers and extending the length of the largest of the latter and curving backward through said baffle.

In testimony whereof we affix our signatures in the presence of two witnesses.

JOHANN STANZIG.

RUDOLF KÖNIG.
